(57) **CLAIM**

The ornamental design for a tab, as shown and described.

DESCRIPTION

FIG. 1 is a perspective view the new design for a tab;

FIG. 2 is a front view thereof;

FIG. 3 is a rear view thereof;

FIG. 4 is a right side view thereof, the left side being a mirror image thereof;

FIG. 5 is a top view thereof, the bottom view being a mirror image thereof; and,

FIG. 6 is a perspective view showing the new design for a tab as applied to the leading edge of a roll of tape.

The broken lines in FIGS. 3-6 are included to show a portion of the tape that forms no part of the claimed design.
